UNITED STATES PATENT OFFICE.

JOHN L. CREVELING, OF WHITE PLAINS, NEW YORK, ASSIGNOR TO GOULD COUPLER COMPANY, A CORPORATION OF NEW YORK.

ELECTRIC REGULATION.

1,420,817.

Specification of Letters Patent. Patented June 27, 1922.

Application filed November 1, 1916, Serial No. 128,819. Renewed April 17, 1922. Serial No. 553,920.

To all whom it may concern:

Be it known that I, JOHN L. CREVELING, a citizen of the United States, residing in White Plains, county of Westchester, and 5 State of New York, have invented certain new and useful Improvements in Electric Regulation, of which the following is a description.

My invention pertains to that class of 10 electric regulation wherein it is desired to regulate an electric function in a predetermined manner, and has for a particular object to provide means whereby said regulation will be automatically accomplished. 15 This application is a continuation, in so far as common subject-matter is disclosed, of my application for patent for improvements in electric regulation, Serial No. 74,070, filed January 25, 1916.

20 In the drawing, Fig. I is a diagrammatic representation of one type of electrical system embodying my invention; and

Fig. II illustrates a modification which 25 may be made in the general system por- trayed in Fig. I without departing from my invention.

In Fig. I, 1 represents a dynamo or generator, the positive terminal of which is connected as by lead 2 with the positive 30 terminals of the storage battery 3 and lamps or other translating devices indicated at 4. The negative terminals of the translating devices and the storage battery are connected as by lead 5 with one side of any suitable switch 6, the opposite terminal of 35 which is connected as by wire 7 with one end of the winding or solenoid 8, the opposite end of which is connected as by lead 9 with the negative terminal of the generator.

40 The generator is provided with any suitable exciting means, in this instance indicated as the usual shunt coil 10, having in series therewith a regulating element 11 indicated as a carbon pile. It will therefore be ob-

45 vious that the generator may be regulated by proper manipulation of the pressure applied to the pile 11, which will control the resistance thereof. A pivot 12 carries a bell-crank lever comprising the short arm

50 13 and the long arm 14, while the pivot 15 carries a bell-crank lever having the short arm 16 and the long arm 17. The carbon pile 11 is held by any of the well known supporting means, purposely omitted for 55 the sake of clearness, between the levers

13 and 16, and therefore the pressure upon the pile 11 may be increased by swinging the levers 14 and 17 in a downward direction so as to cause levers 13 and 16 to approach each other. The springs 18 and 19 60 tend to draw the levers 14 and 17 downwardly and increase the pressure upon the pile 11, while the limit of downward movement that may be given the said levers may be adjusted as by screws 20 and 21. If desired, the springs 18 and 19 may be suppressed and weights, as indicated at 22, used in their stead, or such weights may be used in conjunction therewith. 23 is a spring yieldingly connecting the levers 13 70 and 16 and tending to draw the same together. The tension of the spring 23 may be adjusted as by nuts 24. The outer extremities of the levers 14 and 17 are provided with sheaves or rollers 25 and 26 75 which may be engaged by the cores 27 and 28, of iron or other magnetic material, when the said cores are raised sufficiently, and then further upward movement of either of the said cores will cause its respective sheave to be raised in such manner as to lift the lever cooperating therewith and relieve the pressure upon the carbon pile and increase the resistance thereof.

The cores 27 and 28 may be held in their 80 positions of proper alignment by any suitable means, and are preferably provided with dashpots 29 which restrain too sudden movement of the said cores. The core 28 is surrounded by the coil 8 in such manner that energization of the said coil tends to lift the core. The core 27 is surrounded by the coil 30 which is shown in shunt across the generator and which when energized, tends to lift the core 27. The operation of the coil 8 may be adjusted as by means of the variable shunt 31, while the operation of the coil 30 may be adjusted as by means of the variable resistance 32.

In Fig. II like numerals are used to indicate like parts, and the only modification intended to be brought out by the use of this figure is the coil 33 which may be used in place of coil 8 of Fig. I, in which event the coil affecting the core 28 will be responsive to current in the battery circuit only, while the coil 8 of Fig. I is responsive to the total generator output.

The main switch 6, the mere presence of which is diagrammatically indicated, is pref-

erably one of the automatic variety, closing its circuit when the generator voltage is substantially equal to that of the storage battery, and opening the circuit when the generator voltage falls very slightly below that of the battery so as to prevent back discharge from the battery through the generator. As such switches are well known in the art, details are purposely omitted for the sake of brevity.

An operation of my invention is substantially as follows, referring particularly to Fig. I:

If the generator 1 be at rest or running at low speed, its voltage will be below that of the storage battery 3 and switch 6 will be open and the translating devices 4 may be supplied by the battery 3 in a well known manner. If the generator have its speed brought up until its voltage is slightly in excess of that of the battery, switch 6 will close and current will then flow from the generator to the battery and translating devices, returning to the generator through coil 8, and thereby causing the same to tend to raise the core 28. And I so adjust the tension of spring 19, spring 23 and adjustable shunt 31, or whatever instrumentalities may be employed for the purpose of adjustment, that when the current supplied by the generator, which of course will tend to increase with an increase in speed, reaches a predetermined maximum, as for example the maximum current desired to have delivered by the generator, this output will, by raising the core 28 and bringing the same into contact with sheave 26, and then by swinging the lever 17 in an upward direction, swing the lever 16 in a direction away from the pile 11 so as to decrease the pressure thereupon and cut down the generator field and prevent this maximum desired current from being exceeded. Throughout this operation lever 14 will rest upon its stop 20, and lever 13 will form an abutment for the opposite end of the pile 11. If, for any reason, delivery of this maximum current controlled by the coil 8 necessitate the maximum desired voltage upon any part of the system, across which may be connected the coil 30, (which in this instance is shown across the generator circuit and therefore practically determining its terminal voltage), I so adjust resistance 32, spring 18 and weight 22, or whichever of such devices may be used, that when the generator reaches this maximum desired voltage, coil 30 will raise core 27 and then lift lever 14 from its stop 20 and swing the lever 13 in a direction away from the pile 11 so as to increase the resistance thereof and prevent this desired maximum voltage from being exceeded.

As soon as the voltage coil begins to lower the generator voltage, the current in the coil 8 will begin to fall off and lever 17 will tend

to settle down upon its stop 21 and core 28 will tend to assume the position shown in the drawing and lever 16 will serve merely as a stop or abutment against one end of the pile 11, while the entire regulation will be performed by the voltage responsive means so long as the current remains below that limited by the solenoid 8 and its cooperating parts. If the rise in voltage across the system be due to the rise in voltage across the battery terminals, owing to the battery having been fully charged, it is desirable when this point is reached that the battery charging current be quite substantially reduced or terminated, more or less abruptly, so as to save a long tapering charging current which would ordinarily take place if the maximum desired voltage were held across the battery terminals, as is well understood in the art. And it will be noted that when the current regulating means is operative and lever 16 is swung away from the pile, the tension of spring 23 upon lever 13 is somewhat increased by the motion of lever 16. Therefore, when the voltage responsive means usurps the function of the current responsive means, it first moves the lever 13 and its cooperating parts against a slightly increased pull of the spring 23, which is relieved as soon as core 28 and lever 17 descend. And, therefore, the voltage responsive means operates against a slightly lower opposition than when it started to usurp the function of regulation, and now holds a slightly lower voltage upon the system than that necessary to bring it into action. And this slight difference in voltage will cause the charging current to fall off quite rapidly and approach zero, as may readily be determined by adjusting the parts in a manner which will be plain to one skilled in the art.

It will be noted that by having the cores normally detached and out of contact with their respective arms or levers, a considerable fluctuation in the magneto-motive force of either coil may take place without in any way affecting the regulating apparatus so long as the magneto-motive force is insufficient to raise its core; and after the core is brought into contact with its respective lever, adjustment of the spring or weight or both, or whatever means may be employed, may then determine to a nicety the exact magnetomotive force necessary to operate the regulator.

The operation of that modification intended to be brought out by use of Fig. II is substantially the same as the operation above with respect to Fig. I, with the exception that it is the current in the battery charging circuit that is limited through the instrumentality of the current responsive means, including coil 33 instead of coil 8 of Fig. I, and, therefore, the battery charging

current will be limited, instead of the total generator output; and in such an arrangement it is obvious that the battery charging current may be made to fall off even more rapidly when the voltage responsive means usurps the function of regulation than in the system of Fig. I when the translating devices are in circuit.

From the foregoing it will be noted that my invention produces a system wherein the current delivered by the generator to a particular circuit, as for example the main circuit or the battery circuit, may be held from exceeding a predetermined desirable limit, and wherein the voltage across a circuit, as for example across the generator terminals or the battery terminals, may be held from exceeding a predetermined limit, and that whenever the voltage responsive means usurps the function of the current responsive means, causing the same to go out of action, the voltage responsive means will, due to an effect of its own operation, react upon the system in such manner that the charging current will, in an adjustable degree, be abruptly decreased or terminated.

I do not wish in any way to limit myself to any of the exact constructions or details of operation given above to illustrate one embodiment of my invention, for it will be obvious that wide departure may be made without departing from the spirit and scope thereof which is set forth in the following claims.

35. What I claim is:

1. The combination with regulating means, a plurality of means for affecting the same, and uniting means causing cooperation therebetween, of voltage and current responsive means capable of movement without affecting said affecting means and capable of affecting the same under predetermined conditions.

2. Means for regulating an electric circuit comprehending circuit affecting means, a plurality of means for affecting the same, movable means capable of movement without affecting said means, current and voltage responsive means for moving said movable means into operative relation with the affecting means to regulate said circuit, and means whereby the movable means cooperate.

3. Means for regulating an electric circuit comprehending circuit affecting means, a plurality of means for affecting the same, movable means capable of movement without affecting said means, current and voltage responsive means for moving said movable means into operative relation with the affecting means to regulate said circuit, and ad-

justable means whereby the movable means cooperate in the control of the circuit affecting means.

4. Means for regulating an electric circuit comprehending circuit affecting means, a plurality of means for affecting the same, movable means capable of movement without affecting said means, current and voltage responsive means for moving said movable means into operative relation with the affecting means to regulate said circuit, and resilient means whereby the movable means cooperate in the control of the circuit affecting means.

5. Means for regulating an electric circuit comprehending circuit affecting means, a plurality of means for affecting the same, movable means capable of movement without affecting said means, current and voltage responsive means for moving said movable means into operative relation with the affecting means to regulate said circuit, means whereby the affecting means cooperate in regulating said circuit, and means for independently and mutually adjusting the relationship between said operating means.

6. Means for regulating an electric circuit comprehending circuit affecting means, a plurality of means for affecting the same, movable means capable of movement without affecting said means, current and voltage responsive means for moving said movable means into operative relation with the affecting means to regulate said circuit, means whereby the affecting means cooperate in regulating said circuit, and means for independently and mutually adjusting the relationship between the operation of the responsive means.

7. The combination with regulating means, a plurality of separately movable means capable of separately affecting the same and uniting means causing cooperation between said affecting means, of a plurality of responsive means each capable of movement without affecting said affecting means and affecting the same under predetermined conditions of operation.

8. The combination with regulating means, a plurality of separately movable means each separately affecting the same and uniting means causing cooperation between the affecting means, of a plurality of responsive means each capable of movement without affecting said affecting means and each capable of engaging one of the affecting means and operating the same under predetermined conditions.

JOHN L. CREVELING.
